UNITED STATES PATENT OFFICE

2,135,888

INSTALLATION OF RAIL BONDS

Harold H. Febrey, South Orange, N. J., assignor
to The American Steel and Wire Company of
New Jersey, a corporation of New Jersey

Original application December 8, 1933, Serial
No. 701,521. Divided and this application
February 4, 1936, Serial No. 62,366

1 Claim. (Cl. 29—155.55)

My present invention relates to the installation of rail bonds of the solid stud terminal type and is a division from my co-pending application entitled "Rail bonds", filed December 8, 1933, and bearing Serial No. 701,521.

A bond of this type conventionally includes a conductor strand furnished with a pair of solid copper terminals, the latter providing solid copper studs which are relatively long as compared to their widths and are adapted for insertion and subsequent expansion in holes formed in the rails being bonded. Expansion is effected by a powerful and heavy screw or hydraulic compressor which squeezes the studs to shorter lengths by engaging their ends and the bodies of the terminals proper. Since holes extending completely through the rails are required to expose the ends of these studs, the installation is limited to the webs of the rails.

The above type of bond has not been entirely satisfactory for a number of reasons. One is the erratic installations effected by the compressor, known gages having proven quite insufficient for the purpose of accurate pressure regulation. Another is that excessively long conductors are required to span the splice bars, this being necessary because of the web installations. A further reason is that, even when properly installed, a bond of this character is subject to failure under service conditions, temperature changes causing the copper studs to loosen sufficiently to allow water seepage and a consequent conductivity decrease.

With the intention of remedying the above troubles, I provide an installation method for a terminal provided with a solid stud, which is adapted for insertion and subsequent expansion in a railroad rail, which is characterized in that the stud is inserted into this opening and subsequently expanded by penetration. Since the projectile will ordinarily have relatively little weight, it follows that its velocity must be rather high, for instance, three thousand or more feet per second.

One feature of the above is that relatively small charges of an explosive may be used to propel the projectile to the desired velocity and that, in the case of a number of installations, these charges may be easily proportioned to produce equal velocities in each and every instance, this producing identical penetrating forces at all times if the same projectile, or a number of projectiles of equal weight, is used. In other words, a gun of suitable design provided with a number of cartridges which are similarly charged with a

suitable explosive, and which handles a single captive projectile, or a number of free projectiles of equal weight, may be used to expand the studs of solid stud terminal rail bonds, by penetration of the same, each and every stud being thereby equally expanded.

Further, the penetration possibilities of an explosively propelled projectile are practically unlimited, as is evidenced by the performance of modern military firearms. This permits the further improvements in the installation and construction of a bond of the solid stud terminal type, consisting in forming recesses in the sides of the heads of the rails being bonded, and constructing the bond terminals so that they provide solid studs which are wider than they are long, these studs being insertable into the recesses mentioned. Then, by shooting a projectile completely through the bodies of the terminals and into the studs, by means of explosives, the studs are expanded to complete the installations. Since this permits installation of the bond to the heads of rails, shorter conductor strands may be used.

I further improve on the terminals themselves by constructing them so they provide solid steel studs, or by making the terminal bodies and studs integral and of solid steel. These terminals may be easily fastened in openings in the steel rails, and will not loosen because they expand and contract equally with these rails.

Referring now to the specific examples of terminals and various installations of the same as illustrated by the accompanying drawings:

Figure 1 is a longitudinal sectional view of a rail bond terminal as it appears when installed by my method to the head of a rail.

Figure 2 is a cross-section from the line II—II in Figure 1.

Figures 3 and 4 are longitudinal sectional views showing my installation method.

Figures 5 and 6 are sectional views showing a gun suitable for use with my method.

Figures 7 and 8 are sectional views showing modifications of the terminal installation shown by the first two figures.

Figures 9 and 10 show my method as applied to rail web installations.

Figure 11 is a sectional view showing a completed web installation.

Figures 12 and 13 show modifications of Figures 9 and 11.

Referring particularly to Figures 1 and 2—

The numeral 1 designates a railroad rail. It is to be assumed that this is the end portion of

the rail which is closely adjacent the end portion of another rail, the two rails being spliced together and requiring electrical bonding.

A recess 1^a is formed in the head of the rail 1.

- 5 The bond consists of a conductor strand 2 furnished with a terminal 3, the latter providing a flattened portion 3^b from which a stud 4 projects. This stud is closely fitted into the recess 1^a . The conductor 2 is, of course, provided with another 10 similar terminal at its other end which is similarly installed to the other rail.

Figures 3 and 4 show how this terminal was installed. Figure 3 shows a projectile 5 about to penetrate through the flattened portion 3^b of the terminal 3 and into the solid stud 4. This projectile is moving at high velocity, as has already been described. In Figure 4, the flattened portion 3^b has a relatively deep depression 3^c formed in it for the purpose of relieving the projectile 3 from the work required to force its way through this portion. It is apparent that any expansion of the terminal which occurs outside of the recess 1^a is relatively useless. As previously explained, the stud 4 can be of solid steel. 25 Preferably, the entire terminal is constructed of solid steel so that the flattened portion 3^b and the stud 4 are solid integral parts.

The gun illustrated by Figures 5 and 6 is intended to be merely suggestive of one suitable 30 type. It includes a piston 6 which is fixed to the end of the projectile 5 and slides in a chamber 7. A spring 8 functions to retract the projectile after it has done its work. It is apparent that with this type of gun the projectile is removed 35 after each operation and subsequently reused. Hence, its weight may be considered a constant factor, leaving only its velocity to be considered. In case free projectiles are used, care should be taken to proportion them so that they all have 40 equal weights.

The projectile 5 travels in a barrel 9 formed in a relatively heavy head 10, the piston 6 being restrained by this head. All the parts mentioned are mounted by a rotative frame 11 which turns 45 in a breech part 12. A passage 13, which connects with the chamber 7, is chambered to receive one of the cartridges 14 carrying the explosive charges. These cartridges may be constructed similarly to the blank cartridges furnished by ammunition manufacturers. However, greater care should be taken in proportioning the explosive charges in each, to the end of securing 50 absolutely uniform explosive forces.

Continuing, a firing pin 14 a is positioned by the 55 part 12 so as to strike the cartridge in the chamber 13, it being assumed that the cartridges used are primed in the usual manner. A hammer 15 is urged to cam-like engagement with the pin 14 a , by a spring 16, a suitable trigger mechanism 60 17 providing the necessary control. The part 12 should also be provided with a suitable handle 18 whereby proper manipulation may be effected.

In the operation of the just described gun, a cartridge is inserted, the hammer cocked and 65 the head 18 is properly centered on the flattened portion 3^b of the terminal. Firing causes the projectile 5 to perform its function and then immediately return to its initial position. The necessary pressure release in the chamber 7 may 70 be obtained through properly positioned vent holes 11 a .

It is to be understood that the advantages of the above are particularly great when a large number of rail bond installations are necessary. 75 Since the gun is relatively light, only one work-

man is required. Also, because the cartridges 14 may be loaded so that equal velocities are always imparted the projectile 5, which is itself of constant weight, absolutely the same quality of installation always results. In installing a number of bonds, openings are found in the rails at appropriate points. The bonds are arranged with their terminal studs in these openings and the projectile, or projectiles, are shot into these studs.

Figure 7 illustrates a modification wherein the recess 1^a is provided with an annular groove 1^b . Figure 8 shows the recess as having internal screw threads 1^c . Such modifications may prove advantageous where extreme service conditions are encountered.

Figure 9 shows my installation method as applied to fixing a solid stud terminal 19 to the web of a rail 20. In this case a hole is formed completely through the web and a free projectile 21 is shot through the terminal into the solid 20 stud 19 a .

Figure 10 shows a modification of Figure 9 in that a relatively deep depression 19^b is formed in the flattened portion which lies outside of the hole through the web.

Figure 11 shows the completed installation, with the projectile 21 embedded in the terminal.

Figures 12 and 13 show an installation similar to that shown by Figures 9 and 11, excepting that the projectile 21 is shot directly into the terminal stud. That is to say, it is fired into the opposite side of the terminal and travels through the stud 19 a before it reaches the exterior body portion of the terminal.

Now it should be noted that the captive projectile 5 is provided with a pointed conical portion 5^a and a flattened portion 5^b . Penetration of the portion 5^a starts a flow of metal which might tend towards dislodgement from the recess 1^a , but this tendency is immediately overcome when the shoulder 5^b strikes the terminal, since a force is then exerted against the surface of the terminal which retards such outward flow of metal. Due to the extremely high velocity of the projectile 5, this force is exerted practically simultaneously with the penetration of the projectile's conical portion 5^a .

The free projectile 21 is shown without such a flattened portion, the extra force not being considered necessary in the case of a stud positioned completely through a hole in the web of a rail. In connection with the use of this free projectile, it should be noted that projectiles of the free type may also be pointed and that, when embedded in the terminal, a solid unit is formed with the metal of the terminal in intimate contact with the pointed portion of the projectile.

It should be noted that all the solid terminal studs illustrated are so proportioned that their widths are greater than their lengths. This results from the fact that their lengths need not be great, even in the case of those intended for web installations, while their widths must be sufficiently great to permit of the penetration of a projectile. Also, that the sides of the various studs illustrated are in all cases straight and parallel, this being for the purpose of permitting their free insertion during their installation. In all cases where depressions are formed in the flattened portions of the terminal, the depressions should be arranged substantially in line with the solid studs.

I claim:

A method of installing a rail bond having a terminal providing a solid stud adapted for insertion in an opening formed in a railroad rail, including inserting said stud in said opening, shooting a projectile into said stud by means of an explosive and, practically simultaneously with

the penetration of said projectile into said stud, exerting sufficient force against the surface of said terminal to retard the outward flowing from said opening of metal displaced from said stud by penetration of said projectile.

HAROLD H. FEBREY.
